UNITED STATES PATENT OFFICE.

CHARLES FRANK BUCKLAND, OF DENVER, COLORADO.

CONVERTIBLE MOTOR AND PUMP.

1,086,803.

Specification of Letters Patent. Patented Feb. 10, 1914.

Application filed May 3, 1912. Serial No. 694,820.

To all whom it may concern:

Be it known that I, CHARLES FRANK BUCKLAND, a citizen of the United States, residing at the city and county of Denver 5 and State of Colorado, have invented certain new and useful Improvements in Convertible Motors and Pumps; and I do declare the following to be a full, clear, and exact description of the invention, such as 10 will enable others skilled in the art to which it appertains to make and use the same, reference being had to the accompanying drawings, and to the characters of reference marked thereon, which form a part of this 15 specification.

My invention relates to improvements in convertible motors and pumps.

My improvement consists in a motor adapted to be operated by air taken from 20 a pressure tank, the air being compressed in the tank by the reverse action of the starting motor. Provision is made for connecting the motor shaft in operative relation with the engine shaft for starting purposes, 25 and also for connecting the engine with the motor for compressing the air within the tank.

In my improved construction of motor, a 30 rotary valve is mounted at the outer extremities of the cylinders whereby the latter are placed in communication with and cut off from the supply of air under pressure at properly timed intervals in order to operate the pistons of the several cylinders in such 35 succession as to give the best results, provision being made for automatically opening normally closed valves located in the hollow piston-heads of the cylinders, the valves remaining closed during one stroke and open 40 during the other stroke, the pitmen of the several pistons having lever-arms projecting beyond the connection of the pitmen with the pistons, whereby the pivot pins form fulcrums for levers composed of the pitmen 45 and the extension-arms, which are arranged to alternately act upon and release the valves of the piston-heads.

When the motor is used for engine-starting purposes, the valves in the piston-heads 50 remain closed during the inward movement of the pistons within their cylinders and are held open during their outward movement for exhaust purposes, the exhaust being through openings in the crank-case. On 55 the other hand, when the motor is used as a

compressor and its crank-shaft run in the reverse direction, the valves in the piston-heads remain open during the inward movement of the said heads to allow air to enter the cylinders, while the said valves are closed 60 during the outward movement of the piston-heads, whereby the air which has entered the cylinders by way of the crank-case is driven out of the cylinders and into the air-tank, a check-valve being employed in the 65 conduit leading to the said tank.

Having briefly outlined my improved construction, I will proceed to describe the same in detail, reference being made to the accompanying drawing in which is illustrated 70 an embodiment thereof.

In this drawing Figure 1 is a top-plan view of my improved motor shown in connection and arranged in operative relation with an internal-combustion engine, the 75 various elements including the air-tank, being conveniently located in accordance with a possible arrangement upon the framework of an automobile, or similar self-propelled vehicle. Fig. 2 is a vertical section 80 taken through my improved motor, the parts being shown on a larger scale than in Fig. 1. This section is taken approximately on the line 2-2 Fig. 1. Fig. 3 is 85 a section taken through the motor on the line 3-4 Fig. 2, showing the piston of one of the cylinders at its forward limit of movement. Fig. 4 is a section taken on the same line showing the piston at its outward limit of movement, or in the same position 90 as the piston of the cylinder farthest to the right in Fig. 2.

The same reference characters indicate the same parts in all the views.

Let the numeral 5 designate my improved motor considered in its entirety, the same being composed of a number of cylinders 6, 7 and 8, in which are located hollow piston-heads 9, the cavities of the said heads being designated 10. The outer extremity of each of these heads is provided with an opening 12 which is normally closed by an outwardly-opening check-valve 13, equipped with a stem 14 passing through the hub 15 of a spider 16 located at the inner extremity of the opening in the piston-head and preferably cast integral therewith. The stem 14 of each valve extends inwardly into the cavity of the head beyond the hub 15 and terminates at its inner extremity in a disk 17, be- 105

105

110

tween which and the spider is located a spiral spring 18, which normally acts to hold the valve in its seated or closed position, the opening 12 of each piston-head being surrounded by a beveled wall to harmonize with the beveled edge of the valve 13.

Connected with the inner extremity 19 of each piston-head is a pitman 20, the outer extremity of the pitman having a hub 21 through which passes a pin 22 which is fast in the said head. Beyond the head 21 of the pitman and extending outwardly into the cavity 10 of the piston-head is an arm 23 having an anti-frictional roller 24 at its outer extremity. This arm forms a slight angle with the body of the pitman whereby, when the latter is in alignment with the axis of the cylinder, the roller 24 of the lever-arm is just in contact with the disk 17 of the valve. If we assume that the piston-head in any cylinder is at its outward limit of movement, and that the piston is in the axially-aligned position, the valve in the piston-head will be closed, and if the crank-shaft 25 of the motor is turning toward the right (see Figs. 3 and 4) or in the direction to start the engine, the extremity 24 of the lever-arm 23 will be thrown away from the disk 17 of the valve, allowing the latter to remain in the closed position (see dotted lines in Fig. 3) until the piston is at its inward limit of movement and the pitman has reached its opposite position in axial alignment with the cylinder. As soon as this occurs, the roller extremity 24 of the arm 23 will be in position to begin opening the valve 13, and as the pitman continues its movement in the direction of arrows *a* in Figs. 3 and 4, the roller 24 will act on the disk 17 to open the valve, whereby the latter will be wide open by the time the pitman reaches the full-line position in Fig. 3, and the valve will be kept open until the piston reaches its outward limit of movement in order to allow the air to exhaust from the cylinder into the chamber 26 of the crank-case 27 whence it exhausts through an outlet 28 communicating with the atmosphere. From this it will be understood that when the motor is used for engine-starting purposes, the air will enter each cylinder at its outer extremity and act on its piston-head to move the latter inwardly to its inward limit of movement and as soon as the piston-head begins its outward stroke, the roller extremity of the arm 23 of the pitman will act upon the valve 13 to open the latter and allow the air to exhaust, the piston-heads in the several cylinders being so arranged that one of the heads will at all times be moved inwardly, therefore acting directly to rotate the motor-shaft 25.

The top of the motor beyond the cylinders is equipped with a cylindrical valve-casing 29 in which is located a rotary valve 30,

whose axis is disposed at right angles to the axes of the cylinders. This valve is provided with cone-shaped bearing parts 31, 32 and 33, between which, cavities 34 and 35 are interposed to reduce the bearing surface 70 of the valve. The beveled portions of the valve engage seats of corresponding shape formed on the inner wall of the valve-casing. As the beveled portions of the valve are all correspondingly inclined, it is practicable to arrange the valve so as to automatically compensate for wear upon its bearing parts, and this is accomplished by locating a tension spring 36 in a cavity 37 at one extremity of the valve, a plunger 38 being also located in the said cavity and acted on by a screw 39 threaded in one extremity of the valve-casing and adjustable to regulate the tension of the spring 36 by the movement of the screw toward or away 80 from the plunger 38.

Surrounding the hollow stem 40 of the valve is a steel collar 41, between which and a collar 42, fast on the framework of the motor, are interposed bearing-balls 43 to reduce the friction on the rotary valve, the latter being actuated by a flexible device 44 leading from a wheel on the motor-shaft 25 to a similar wheel with which the stem of the rotary valve is equipped. This valve 90 is provided with ports 45 suitably spaced circumferentially, and all communicating with a longitudinal cavity 46 formed in the valve and opened at one extremity as shown at 47 to communicate with a chamber 48, the latter being in communication, through a port 49, with an air-pipe 50 which is in communication with a tank 51 containing air under pressure. Within this pipe 50 is located a valve 52 normally spring-held in the closed position, the valve being equipped with a crank-arm 53 which is connected by means of a spring 54 with a stationary bracket 55. When it is desired to admit air under pressure to the longitudinal cavity 46 of the rotary valve, the valve 52 is manually opened through the medium of a rod 56 leading from the arm 53 of the valve to an arm 57 of a lever 58, the opposite arm 59 of the lever having a hand-piece 60 within convenient reach of the person in charge of the machine, the lever being normally held in a position corresponding with the closed position of the valve by means of a spring 61.

The valve-casing is provided with passages 62 which register with passages 63 formed in the outer extremities of the cylinders, the two passages 62 and 63 corresponding in location with that of the several cylinders, being respectively in register with the several ports 45 of the rotary valve during a portion of each revolution of the valve, the ports 45 being circumferentially spaced as heretofore explained to se- 100 115 125 135 140

cure harmonious action of the several piston heads as they coöperate under the influence of the air-pressure to rotate the motor crank-shaft 25.

5 Referring now to the use of the motor in connection with an engine 64 on a vehicle 65, the engine-shaft 66 is equipped with a gear 67, suitably located to mesh with a gear 68 splined on the motor shaft 25 and adapted 10 to be moved into engagement with the gear 67 through the medium of two levers 69 and 70, and a connecting rod 71. The lever 69 is fulcrumed on the frame-work of the machine as shown at 72, and engages in operative 15 relation a circumferential groove 73 formed in the hub 74 of the gear 68. One extremity of this lever is connected as shown at 75 with one end of the rod 71, while the opposite end of the said rod is connected as 20 shown at 76 with one arm of the lever 70, the opposite arm of the lever being equipped with a hand-piece 77 conveniently accessible to the chauffeur. If we assume that the motor is in operation and that the crank-shaft is 25 turning in the direction of the arrows A in Figs. 3 and 4, if the gear 68 be thrown into mesh with the gear 67, the engine-shaft will be turned for starting purposes, and as soon as the engine is started the gear 68 will be 30 disconnected from the gear 67 and the air may be cut off from the motor by closing the valve 52. Now if it is desired to charge the tank 51 with compressed air, a gear 78 normally loose on a shaft 79 of the engine. 35 is thrown into engagement with a cone 80 fast on the said shaft whereby the gear will be rotated by friction, the gear 78 being simultaneously thrown into mesh with a gear 81 on the crank-shaft 25 of the motor. The 40 shaft 79, which is the magneto-shaft of the engine, serves as a sort of counter-shaft interposed between the engine-shaft and the motor-shaft, the engine-shaft being connected in operative relation with the shaft 79 45 by gears 82 and 83.

The gear 78 is manipulated by means of a rod 84 leading from a yoke 85 to a lever 86 fulcrumed on a shaft 87. The yoke 85 is fulcrumed on a bracket 88 so that as the 50 lever 86 is properly manipulated, the gear 78 will be shifted to frictionally lock it on the shaft 79 and simultaneously throw it into mesh with the gear 81 of the motor. This will set the motor in operation so that 55 its crank-shaft 25 will be rotated in a direction reverse of that indicated by the arrows A in Figs. 3 and 4, and in this event the valves 13 of the several piston-heads will remain open during the inward movement 60 of the said heads to allow the air to enter the outer extremities of the cylinders from the crank-case which is open to the atmosphere through outlets 28, as heretofore explained. Then, as each piston-head begins 65 its upward movement, the valve is closed

and the piston-head forces the air out of the cylinder, the parts 45 of the rotary valve being properly arranged for this purpose in each instance, the air being forced from the cylinders through the rotary valve and the conduit 50 into the air-tank 51, a by-pass 89 being connected with the conduit 50 and extending around the normally closed valve 52, a check-valve 90 being located in this by-pass to allow the air to pass to the tank 51 but preventing its return. 70

In order to properly and automatically lubricate the rotary valve, a pump 91 is employed, the same consisting of a plunger 92 reciprocated from an eccentric 93 connected with the plunger as shown at 94, an arm 95 leading from the strap 96 of the eccentric for the purpose, the eccentric being mounted on the motor crank-shaft 25. The plunger 92 works in a small chamber 97 in communication with the oil 98 of the crank-case by means of a short pipe 99 having a check-valve 100 opening inwardly to allow oil to enter the chamber 97 as the plunger moves inwardly, the said oil being forced through a pipe 101 having an outwardly-opening check-valve 102 at the outer extremity thereof, whence the oil in the conduit 103 from which it leads to a branch pipe 104, passes, the latter in turn having short branches 105 which lead to the cavities 34 and 35 surrounding the rotary valve. The oil introduced to these cavities is under sufficient pressure to cause it to work in between the bearing surfaces of the valve 30 and its casing 29, or into engagement with the bearing-parts 31, 32 and 33 of the valve. When the cavities 34 and 35 are full and the pump continues its operation, the pressure of the oil within the pipe 103 will be sufficient to open a normally closed check-valve 106 located at the upper extremity of the pipe 103. This check valve is provided with a screw-cap 107 which may be adjusted to regulate the pressure at which the valve will 100 open. When this valve opens, the oil escapes and is thrown over the flexible device or chain 44 and thoroughly lubricates the parts in connection therewith. The oil is also brought into communication with the 105 ball-bearings 43 between the valve and its casing. 110

Having thus described my invention, what I claim is:

In a multi cylinder motor, a valve casing 120 provided with a plurality of cone shaped bearings the larger extremity of each bearing being of a diameter no greater than the smaller extremity of the next larger bearing and said bearings being arranged progressively as to size, each of said bearings having a port therethrough communicating with one of the cylinders of the motor, a valve piece rotatably mounted within said casing 125 and having cone shaped portions adapted to 130

engage said bearings, said valve piece being hollow throughout a portion of its length and having ports extending through said cone shaped portions into the hollow interior of the valve piece, said hollow interior being in communication with a fluid pipe.

In testimony whereof I affix my signature in presence of two witnesses.

CHARLES FRANK BUCKLAND.
